(57) CLAIM

The ornamental design for a novelty dragon shoe, as shown and described.

DESCRIPTION

FIG. 1 is a front perspective view of a novelty dragon shoe showing our new design;

FIG. 2 is a front elevation view thereof;

FIG. 3 is a rear elevation thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in FIGS. 1-7 depict environmental elements only and form no part of the claimed design.

1 Claim, 4 Drawing Sheets
